BUTTON MACHINE SAW FILING DEVICE

Willard C. Protsman, Lansing, Iowa

Application May 23, 1934, Serial No. 727,160

4 Claims. (Cl. 76—31)

My invention relates generally to button sawing machines, and particularly to an attachment for mounting thereon enabling quick and accurate sharpening of the teeth of the button saw without removing the button saw from the machine.

It is an important object of my invention to provide a button saw filing attachment which is capable of being positioned entirely out of the way of the operator of the machine while the attachment is not in use; and capable of being instantly brought into operative position for filing the button saw of the machine, without removing the button saw from its position in the machine.

Other objects and advantages of my invention will be apparent from a reading of the following description in connection with the drawings, wherein for purposes of illustration I have shown a preferred embodiment of my invention.

In the drawings:—

Figure 1 is a side elevational view of a portion of a button sawing machine showing the attachment of the invention applied thereto and in its operative position.

Figure 2 is a top plan view of Figure 1.

Figure 3 is an elevational view taken from the right of Figure 1 and looking toward the left and showing the file in position in the attachment and the relation of the file to the button saw of the machine.

Figure 4 is a transverse vertical sectional view taken substantially on a line 4—4 of Figure 1 through a portion of the button making machine showing the stationary mounting thereon of a portion of the device of the invention.

Figure 5 is a horizontal sectional view taken substantially on a line 5—5 of Figure 3 and showing the means for indicating when the teeth of the button saw have been filed to the proper depth, thereby enabling uniformly filing each of the teeth of the button saw.

Figure 6 is a perspective view of the swingable retaining dog.

Figure 7 is a perspective view of a portion of the stationary frame of the device.

Figure 8 is an enlarged longitudinal vertical sectional view taken substantially on a line 8—8 of Figure 1 showing the manner of engagement of the swingable dog of Figure 6 with the teeth of the plates which are connected to the pulley of the button making machine.

Figure 9 is a transverse vertical sectional view taken substantially on a line 9—9 of Figure 8

showing the said plates in elevation and the manner in which they are mounted in the pulley.

Figure 10 is an elevational view similar to Figure 9 with the said plates removed.

Figure 11 is a perspective view illustrating a button saw with the file engaged therewith at such an angle that the file engages one side of rather than diametrically opposite sides of the button saw.

Figure 12 is a fragmentary side elevational view of the button saw.

Referring in detail to the drawings, the numeral 5 refers generally to the pertinent part of the button making machine having the rotatable horizontal shaft 6 on which is fixed the pulley generally designated 7, the shaft 6 being mounted on the U-shaped standard generally designated 8 which includes on the upper end of each leg a removable bearing cap 10 which rests on a flange 10'. An inverted U-shaped member 11 rests the lower ends of its legs on the bearing cap 10 so that its bight portion 11' forms the horizontal support for the transverse horizontal portion 12 from which depend screws 13, 14 which traverse the bight portion 11', the bearing cap 10 and the flange 10', below which they are provided with nuts 13' and 14', respectively, which are arranged to be tightened against the lower surface of the flange 10' to hold the described organization in place.

On one end of the member 12 is the short vertical arm 12' and on the opposite end the inverted J-shaped member generally designated 15. The member 15 and the member 12' have horizontally aligned holes 16 and 16', respectively, to receive the axially rotatable shaft 15'. The opposite ends of the shaft 15' extend beyond the elements 15 and 12', respectively, and outwardly of the element 12' the shaft 15' traverses the arm 28, and outwardly of the element 15 the shaft 15' traverses the companion arm 27, which arms have their right hand extremities joined by the cross bar 20 to form a swingable frame pivotally supported at one end by the shaft 15'. Set screws 25 and 26 traversing the arms 27, 28, respectively, lock the said side members on the described portions of the shaft 15'.

The lower part of the J-shaped element 15 has vertically spaced holes 15a and 15b, respectively, through which are arranged the clamping bolts 50 68 and 70, respectively. The bolts also pass through the slot 67 in the lug 68', and through the slot 71 in the rest 69, respectively, so that the lug 68' and the rest 69 may be vertically adjusted with respect to the J-shaped element 15. 55

It will be obvious that by adjusting the lug 68' vertically a position thereof may be arranged wherein the swingable frame referred to will be supported at the proper level with the arm 27 resting on the top of the lug as shown in Figure 1. It is also obvious that the rest 69 which is adapted to have its lower end supported on and rising from the bed 72 of the button making machine may be adjusted relative to the J-shaped element to afford proper support thereto while the swingable frame is in the operative position shown in Figure 1.

A bolt 39 and a bolt 31 project laterally outwardly from the arms 28, 27, respectively, of the swingable frame and engage through longitudinally arranged slots in the extension arms 32, 33. The bolts 30, 31 may be tightened to clamp the arms 32, 33 in differently extended positions in longitudinal alignment with the side members 28, 27, respectively, to adjust the file carrying frame toward and away from the button saw. It is to be observed that the extension arm 32 is longer than the extension arm 33 and that these arms are joined and rigidly connected by the bar 34.

Rotatably mounted in the outward extremities of the extension arms 32, 33 and thereby having a biased horizontal position is the rotatable shaft 42 on which is fixed the file carrying frame. The shaft 42 has the depending handle 65 for swinging the file carrying frame toward and away from the button saw, and for sliding the shaft 42 transversely in opposite directions. The shaft 42 has thereon buffers 45, 46 which include the resilient blocks 47, 48, respectively, and the locking screws 49, 50, respectively, with the resilient blocks arranged to strike the extremities of the extension arms 32, 33 at opposite ends of the adjusted stroke of the shaft 42 to prevent jar and unnecessary wear and to accurately limit the length of the stroke of the file.

The file carrying frame comprises the plate 44 whose upper end is wrapped around the shaft 42 to form a journal including the set screws 42 to 63 for locking the plate 44 to a selected position of the shaft 42 between the buffers; and, the plate 44 has fixed to the back thereof the vertical transversely elongated flat bar 54 on whose front side are fixed the depending blocks 56, 56' which have square cut holes receiving the file as indicated in the drawings, particularly Figure 3, the file 57 being of the three-cornered variety. Set screws 60 and 61, respectively, traverse the lower ends of the blocks 56, 57 and engage the file 57 to lock the same in position.

Horizontally traversing the plate 44 is the stop screw 52 (see particularly Figures 3 and 5) the end of which is arranged to be engaged by the semi-flexible blade 37 on the arm 36 which is pivoted on the center pivot 35 of three pivots which traverse and depend from the cross member 34 which extends between the extension arms 32, 33. The pivot or anchor 39 has fixed thereto the leaf spring 38 which acts against one side of the arm 36 and forces it yieldably in a clockwise direction as shown in Figure 5, while the pivot 40 has a lateral part which bears against the opposite side of the arm 36 and acts as a stop which is to be engaged by the arm 36, the stop 40 being adjustable by pivoting it. It will be obvious that as the plate 44 is reciprocated transversely in operating the file that as the tooth of the button saw being filed wears down the saw carrying frame will be permitted to move toward the left and the consequence is the

plate 44 will more closely approach the arm 36. With the stop screw 52 adjusted to extend properly through the plate 44 the end of the screw 52 will strike the semi-flexible tip 37 of the arm 36 when the tooth of the saw has been sufficiently filed, so as to produce a clicking noise cooperated in by the arm 36, the spring 38 and the stop 40 when the arm 36 or the tip 37 thereof is struck by the tip of the screw 52, thereby indicating to the operator that the tooth has been sufficiently filed. In this way the operator is informed instantly of reaching a proper depth in the filing of the saw teeth so that each of the teeth of the button saw may be filed to a uniform depth.

Referring specifically to Figures 8 through 12 it will be observed that the pulley 7 has a concentrically formed hollow recess 7' in which the frame 80 is arranged around the shaft 6. The frame 80 comprises upper and lower members 81, 82 and side vertical members 83, 84, the vertical members being attached to the back of the members 81, 82. Also mounted on the back of the members 81, 82 are the L-shaped brackets 85, 86 which have in their foot portions radially outwardly arranged set screws 87, 88 which are engageable with the interior of the recess 7', while similarly mounted L-shaped brackets 89, 90 on the members 83, 84, respectively, have set screws 91, 92 engaging the periphery of the recess 7' similarly to the set screws 87, 88, thereby mounting the frame within the recess of the pulley. Mounted on the front of the members 81, 82 and 83, 84 are the blocks 93, 94, 95 and 96 and to the axially outward end of these blocks are mounted the toothed plates 97, 98, respectively, by means of bolts 99 and 100 which traverse the respective blocks and engage the respective elements of the frame 80, so that the plates 97, 98 are located outwardly of the recess 7' and in a position to have teeth thereof engaged by the swingable dog 17 whose arms 18, 19 have holes 20, 21 receiving the shaft 15' at a point between the end members of the plate 12 as shown in Figure 2. The element 22 directly engages the teeth 101 of the plates 97, 98, and the teeth 101 being arranged so as to be circumferentially positioned in accordance with the position of the teeth of the button saw, the dog 17 acts to hold the shaft 6 in such a position that the pulley 7 may be rotated by hand in a clockwise direction viewed in Figure 9 to bring the teeth of the button saw generally designated 102 into the proper position to be filed.

Each of the plates 97, 98, respectively, is a semi-circular plate. A single plate embodying these elements is avoided and the two plates provided so that the same may be assembled around the shaft 6 easily and quickly and without requiring displacement of the shaft or of the pulley whenever plates of different sizes are required to be used and mounted on the frame 80. It will be obvious that the dog 17 may be swung upwardly out of engagement with the teeth 101 whenever desired.

The button saw comprises the cylinder 103 which is receivable in the chuck 9 on the end of the shaft 6 as indicated by dotted lines in Figures 1 and 2. The tubular button saw proper 104 is slotted as indicated at 105 and is slideable in the cylinder 103 so that it may be adjusted outwardly as wear shortens the saw. An arrangement of a slot 106 and a suitable wedge 106 permits expanding the tubular saw 104 against the inside of the cylinder 103 after ad-

justing the saw and extending the same outwardly of the cylinder 103. The teeth 107 of the button saw are arranged to be filed at an angle less than a right angle with respect to the axis of the button saw, and only one notch defining the adjoining teeth is filed at a time, the position of the three-cornered file 57 being clearly shown in Figures 11 and 12.

As soon as the button saw has been properly filed, the swingable frame is tilted upwardly and pushed toward the left so as to be out of the way of the operator. The said frame does not swing all of the way to the left to a horizontal position but is held at an angle above the pulley by the L-shaped stop 23 which is bolted as indicated at 24 to the J-shaped member 15 which forms a rest for the entire structure carried by the swingable frame. In this out of the way position (not shown) there is no part of the device directly overhanging the chuck 9 or the button saw and the operator of the button sawing machine has completely free access thereto. It is obvious that it is a simple matter to swing the organization described to the position shown in Figure 1 from the inoperative position as soon as it is desired to file the button saw by reciprocating the shaft 42 back and forth while the file is engaged in each notch of the saw until the click is made by the indicating arm 36 which shows, in respect of each notch, when the same has been adequately filed to a uniform depth. Heretofore, it has been necessary to remove the button saw from the button making machine and to replace the same with another saw. This entailed stopping the machine for a considerable time and also entailed the use of skilled and expensive labor for conditioning the button saw for return to be replaced in the machine. All of these time consuming and expensive operations are eliminated in the use of the device of the invention, since with the device of the invention the same operator is enabled to quickly condition his saw as often as he sees fit, without any considerable interruption in the operation of the button sawing machine.

Although I have shown and described herein a preferred embodiment of my invention, it is to be definitely understood that I do not desire to limit the application of the invention thereto, and any change or changes may be made in materials and in structure and arrangement of parts, within the spirit of the invention and the scope of the subjoined claims.

What is claimed is:—

1. In a button sawing machine including an arbor having a chuck mounting a button saw, a bearing supporting said arbor at one side of said chuck; a frame swingably mounted on said bearing and arranged overlying said chuck and said button saw, and button saw filing means pivotally mounted on said frame and audible signaling means associated with the saw filing means to indicate a predetermined filing depth. 5

2. In a button sawing machine including an arbor having a chuck containing a button saw, a bed, a bearing for said arbor rising from said bed, a frame swingably mounted on said bearing, button saw filing means pivoted on said frame and engageable with said button saw, and a foot connected to and depending from said frame and engageable with said bed to support said frame in operative position and audible signaling means associated with the saw filing means to indicate a predetermined filing depth. 10 15

3. A button saw filing attachment for a button sawing machine, said machine including a bearing supporting an arbor containing the button saw, said attachment comprising a frame having extensible sides, a slide bar attached to said sides and arranged to be given different angulations with respect to the axis of the button saw by adjusting the said sides, button saw filing means pivotally and slidably mounted on said slide bar, said means mounting said frame on said bearing for swinging on a horizontal axis into and out of horizontal operative position and audible signaling means associated 20 25 30 35 with the saw filing means to indicate a predetermined filing depth.

4. In a button sawing machine including an arbor having spaced thereon a pulley and a chuck containing a button saw, a bearing supporting said arbor at a point between said pulley and said chuck, a frame swingably mounted on said bearing, button saw filing means pivoted on said frame for engagement with said button saw, a toothed wheel fixed to the side of said pulley facing said chuck and frame, a dog mounted on said frame, said dog being selectively engageable with the teeth of said toothed wheel to hold the arbor and thereby said button saw in selected positions of rotation while filing different teeth of said button saw, and audible signaling means associated with the saw filing means to indicate a predetermined filing depth. 40 45 50

WILLARD C. PROTSMAN.
